COLLAPSIBLE TRAILER AND BOAT COMBINATION

Josef Hartmann, 59 Munsterstrasse, Warendorf,
Westphalia, Germany

Filed Jan. 18, 1966, Ser. No. 658

Claims priority, application Germany Aug. 19, 1965

Term of patent 14 years

(Cl. D14—3)

FIG.1

FIG.6

FIG. 1 is a perspective right side view, when seen in the direction of travel of the collapsible trailer and boat combination, in collapsed or folded state;

FIG. 2 is a perspective right side view of the collapsible trailer and boat combination in the first stage of assembly, showing the boat with particular clarity;

FIG. 3 is a perspective right side view of the assembled collapsible trailer and boat combination;

FIG. 4 is a top plan view of the collapsible trailer and boat combination;

FIG. 5 is a left elevation of the assembled collapsible trailer and boat combination; and

FIG. 6 is a front elevation thereof.

I claim as my invention:

The ornamental design for a collapsible trailer and boat combination, as shown and described.
